UNITED STATES PATENT OFFICE.

HENRY A. WEIHMAN, OF PHILADELPHIA, PENNSYLVANIA, ASSIGNOR TO
JOHN F. SIMONS AND THOMAS MADDOCK, OF SAME PLACE, FREDERICK M. SIMONS, OF SWARTHMORE, PENNSYLVANIA, AND EDWIN S. SIMONS, OF ORANGE, NEW JERSEY.

DESIGN FOR A BRUSH-BACK OR SIMILAR ARTICLE.

SPECIFICATION forming part of Design No. 31,226, dated July 18, 1899.

Application filed April 26, 1899. Serial No. 714,585. Term of patent 3½ years.

To all whom it may concern:

Be it known that I, HENRY A. WEIHMAN, of the city and county of Philadelphia, State of Pennsylvania, have invented a new and useful Design for Brush-Backs or Similar Articles, of which the following is a specification.

My new design for brush-backs, &c., is shown in the accompanying drawing, which is a plan view of a brush-back embodying the design.

10 The body A of the back has on each side a series of torches *a*, springing from one another and bounded internally by a rib *b*, with a foliate capital *c* at the outer end. The inner end of the body is also provided with a foliate ornamentation *d* and the outer edge is bounded by a rib *e*, having small decorative effects *f* adjacent to the top. The central portion *g* is unornamented.

15 The handle B is provided with a similar

decoration, having the torches *a'*, the internal 20 rib *b'*, foliate capital *c'*, the foliate ornamentation *d'* at the inner end, and the outer rib *e'*, with the decorative effects *f'* and the central portion *g'* unornamented.

The essential feature of the design resides 25 in the torch ornamentation in the sides, with the foliate capital.

What I claim as new, and desire to secure by Letters Patent, is as follows:

The design for a brush-back or similar article substantially as described and shown in the accompanying drawing.

In testimony of which invention I have hereunto set my hand.

HENRY A. WEIHMAN.
